UNITED STATES PATENT OFFICE.

GEORGE E. MITCHELL, OF HAVERHILL, MASSACHUSETTS.

DESIGN FOR A CHAIR-ARM.

43,152.

Specification for Design.

Patented Oct. 15, 1912.

Application filed July 10, 1912. Serial No. 708,740. Term of patent 14 years.

To all whom it may concern:

Be it known that I, GEORGE E. MITCHELL, a citizen of the United States, residing at Haverhill, in the county of Essex and State of Massachusetts, have invented a new, original, and ornamental Design for a Chair-Arm, of which the following is a specification, reference being had to the accompanying drawing, forming part thereof.

Figure 1 is a perspective view, Figs. 2

and 3 are elevations of the opposite sides, and Fig. 4 a plan view of a chair-arm showing my new design.

I claim:

The ornamental design for a chair-arm, as shown.

GEORGE E. MITCHELL.

Witnesses:

RALPH H. TAYLOR,
JOHN R. WADLEIGH.
